UNITED STATES PATENT OFFICE.

JOHN F. O'CONNOR, OF CHICAGO, ILLINOIS, ASSIGNOR TO WILLIAM H. MINER, OF CHAZY, NEW YORK.

REFRIGERATOR-CAR DOOR.

1,345,392.

Specification of Letters Patent.

Patented July 6, 1920.

Application filed January 8, 1918. Serial No. 210,881.

To all whom it may concern:

Be it known that I, JOHN F. O'CONNOR, a citizen of the United States, residing at Chicago, in the county of Cook and State of Illinois, have invented a certain new and useful Improvement in Refrigerator-Car Doors, of which the following is a full, clear, concise, and exact description, reference being had to the accompanying drawings, forming a part of this specification.

This invention relates to improvements in refrigerator car doors.

In the operation of refrigerator cars where the same are transported from hot to cold climates and vice versa, it frequently happens that the products being transported in the cars will require being iced during part of their travel and at other parts will require being ventilated without icing. In other words, it frequently occurs that the refrigerator cars must be sealed tight at certain times and at other times it is extremely desirable that openings at the center of the car be provided to permit necessary circulation of air through the cars during the transportation of the same products. So far as I am aware, no adequate means have heretofore been provided for accomplishing the desirable results above indicated.

The object of my invention is to provide a refrigerator car with refrigerator side doors so arranged that the car can be sealed in the usual manner when desired or the side doors so arranged as to provide an air vent and permit circulation of air through the car when desired and at the same time prevent surreptitious removal of any of the car's contents.

In the drawing forming a part of this specification, Figure 1 is a side elevation of a portion of a car wall showing my improvements in connection with the side door thereof. Fig. 2 is a horizontal, sectional view upon an enlarged scale taken substantially on the line 2-2 of Fig. 1. And Fig. 3 is a vertical, sectional view upon an enlarged scale taken on the line 3-3 of Fig. 2.

In said drawing, the side wall of the car is shown as provided with the usual refrigerator door opening which is defined by the threshold 10, side posts 11-11 and lintel 12. On the sides and top of the door opening, insulation is provided, that shown in the drawing being of a well known form and comprising spring pressed portions

13-13 covered over by canvas 14 or other suitable packing material. The door is formed in two parts, A and B in the usual manner, the same having beveled meeting edges and the door B being closed last. Final closure of the door B and the locking of the same in closed position is accomplished in a well known manner by means of a rotatable shaft 15 having crank arms 16-16 at the ends thereof engageable in keepers 17-17 secured to the threshold and lintel of the door. The shaft 15 has an operating handle 18 which is adapted to be locked in closed position by any suitable means and sealed with a lead seal in the usual manner.

To attain the objects of the invention hereinbefore set forth, the door B is provided at its free edge with an auxiliary section 19, the same being pivotally connected to the main body of the door B on the interior of the latter by means of double jointed hinges 20-20. The auxiliary section 19 corresponds in width to the thickness of the door B and is of trapezoidal cross section. At its upper and lower edges, the auxiliary section 19 is beveled as indicated at 21 to form a wedging fit with correspondingly beveled faces 22 on the main portion of the door B. For insulation, a layer of felt or canvas 24 is preferably secured to the vertical inset face 25 of the main portion of the door B.

When the refrigerator car is to be sealed in the usual manner, the auxiliary section 19 occupies the position shown most clearly in Fig. 2 where it forms a seal with the adjacent insulated packing of the door A. To retain the auxiliary section 19 in this position eyes and hooks 26 may be employed, as shown in Fig. 1. In this condition, the door B will be operated and used exactly as the ordinary refrigerator door of present types employed. When, however, it is desired to ventilate the refrigerator car and promote draft of air therethrough, the auxiliary section 19 will be swung inwardly to the position indicated by dotted lines at 119 in Fig. 2, and it can be held in this position by means of other suitable hooks 27. When the auxiliary section 19 occupies the position shown in dotted lines in Fig. 2, it is apparent that an elongated vent is provided between the doors A and B which will permit air entering the ends of the car to pass out 119

at the center of the car through the doors. At the same time, it will be observed that the vent thus provided is comparatively narrow and being on an incline will effectively prevent any malicious withdrawing of the contents of the car, it being understood that the operating handle 18 can be retained at its proper position and protected by a lead seal.

10 With my arrangement, the railroads are enabled to obtain greater service from the refrigerator cars and without any appreciable additional expense. The construction is also simple and the change from one condition to another may be made by railroad operatives without difficulty at any time desired while the car is in transit.

Although I have herein shown and described what I now consider the preferred manner of carrying out my invention, the same is merely illustrative and I contemplate all changes and modifications that come within the scope of the claims appended hereto.

25 I claim:

1. In a railway refrigerator car having a side door opening through which the car is adapted to be loaded and unloaded, of a pair of pivoted, insulated doors adapted to close 30 said opening when the doors are in closed position, said doors having vertically ex-

tending beveled meeting edges, one of said doors having a section of its free beveled edge pivotally connected to the main portion of said door, said section being adapted 35 to be swung to the inner face of the main portion of the door of which it forms a part to thereby leave a ventilating opening between the edges of the two doors when the latter are both in closed position, and means 40 for locking said doors in closed position.

2. In a railway refrigerator car having a side door opening through which the car is adapted to be loaded or unloaded, of a pair of pivoted, insulated doors adapted to close 45 said opening when the doors are in closed position, said doors having vertically extending meeting edges, one of said doors having a section at its free edge movably attached to the main portion of said door, said 50 section being adapted to be moved to a position overlying one face of the main portion of the door of which it forms a part to thereby leave a ventilating opening between the edges of the two doors when the latter are 55 both in closed position, and means for locking said doors in closed position.

In witness that I claim the foregoing I have hereunto subscribed my name this 29th day of Dec., 1917.

JOHN F. O'CONNOR
